UNITED STATES PATENT OFFICE.

SIDNEY A. KELLER, OF NEW YORK, N. Y., ASSIGNOR TO MARCUS T. GOLDSMITH, OF NEW YORK, N. Y.

DESIGN FOR A BRUSH OR MIRROR BACK.

SPECIFICATION forming part of Design No. 35,357, dated December 3, 1901.

Application filed September 21, 1901. Serial No. 76,080. Term of patent 14 years.

To all whom it may concern:

Be it known that I, SIDNEY A. KELLER, a citizen of the United States, and a resident of New York, in the county of New York and 5 State of New York, have invented and produced a certain new and useful Design for Brush or Mirror Backs, of which the following is a specification.

In the accompanying drawings, to which reference is made and which form a part of this specification, Figure 1 is a plan view of my newly-designed brush or mirror back, and Fig. 2 is a cross-section of the same.

The leading feature of my design consists 15 of the representations of the cupids and use of the surface ornamentation as represented by the drawings.

In the drawings, A designates the brush or mirror back, having a plain oval field B at the center. Above the said field B appears the 20 cupid C, with crossed arms and surrounded by foliate scrolls D D. At each side on curved surfaces B' B' appear two other cupids E E, also surrounded by foliate scrolls F F. Below the field B appear a cluster of flowers and 25 other foliation, as shown.

What I claim is—

The design for a brush or mirror back substantially as shown and described.

SIDNEY A. KELLER.
